UNITED STATES PATENT OFFICE.

OLIVER S. JENNINGS, OF WILKINSBURG, PENNSYLVANIA, ASSIGNOR TO WESTINGHOUSE ELECTRIC AND MANUFACTURING COMPANY, A CORPORATION OF PENNSYLVANIA.

REVOLVING FAN.

1,226,076.

Specification of Letters Patent.

Patented May 15, 1917.

Application filed January 6, 1915. Serial No. 788.

To all whom it may concern:

Be it known that I, OLIVER S. JENNINGS, a citizen of the United States, and a resident of Wilkinsburg, in the county of Allegheny and State of Pennsylvania, have invented a new and useful Improvement in Revolving Fans, of which the following is a specification.

My invention relates to rotary electric fans, and it has special reference to gyratory fans that are adapted to turn on an axis of rotation while simultaneously and automatically turning around an axis of revolution.

15 One object of my invention is to provide a simple, inexpensive and rugged fan structure of the above-indicated character which shall be automatically driven around its axis of revolution at predetermined speeds by the reaction forces set up by the rotation of the fan blades.

20 Another object of my invention is to provide convenient means for quickly changing the speed of revolution of the fan structure.

25 A further object of my invention is to provide means for maintaining the several fan structures constituting my device at equal angular relations with respect to the support which carries the fan structures.

30 Figure 1 is a side elevational view of a fan structure embodying my invention and Fig. 2 is a plan view of the structure shown in Fig. 1.

35 The device shown in the drawings comprises a bracket 1 rotatably supported, in any convenient manner, upon a hanger 2 and having outwardly and oppositely extending arms 3 and 4. Secured to the outer

40 ends of the arms 3 and 4 are bearing members 5 and 6 which are adapted to pivotally support, by means of pivot screws 7, a pair of trunnions 8 and 9 in which fan motors 10 and 11 are horizontally pivoted.

45 Thumb screws 12 and 13 are provided to secure the fan motors 10 and 11 in adjusted tilted positions around their horizontal pivots. The armature shafts 14 and 15 of the fan motors 10 and 11 carry sets of fan blades 16 and 17. The details of the rotatable supporting means for the bracket 1 and of the fan motors with their fan blades form no part of my present invention, and will therefore not be further described.

50 As shown in Fig. 1, the bearing members

5 and 6 are slightly inclined from the vertical, the angle of inclination being about five degrees in the structure shown. This inclination is sufficient to cause the fan motors to rotate about these inclined pivots by 60 their own weight when the bracket 1 is at rest, and the direction of such inclination causes the end brackets 18 and 19 of the fan motors 10 and 11 to approach the bracket arms 3 and 4, respectively. The trunnions 65 8 and 9, which carry the fan motors 10 and 11, are connected by a rod 20, one end of which is pivotally attached, at 21, to the trunnion 9, while the other end is pivotally attached, at 22, to a projection 23 formed on 70 the trunnion 8. The points of attachment of the opposite ends of the rod 20 are so disposed that they are equidistant from the inclined pivots 7, and the fan motors are caused to move in unison and in the same direction around the inclined pivots 7. Stops 75 24 are formed on, or attached to, the bearing members 5 and 6 in order to limit the outward pivotal movement of the fan motors which is caused by the starting torque 80 of the motors, when they are tilted downward at starting, and also to limit the effect of centrifugal force while the supporting bracket is rotating. These forces may, unless prevented by the stops, or otherwise, rotate the fan motors far enough outward to bring the thrust axes of the fans up to or beyond the axis of rotation of the bracket, and the revolution of the bracket may thereby be interrupted or reversed. 90

The starting torque of the motors may even throw the motors outward far enough to set the supporting bracket in rotation in the wrong direction. 95
In order to assist centrifugal force in turning the fan motors outwardly around their pivots, I provide a spring 25 that is maintained in tension between a projection 26 formed on the bracket arm 3 and a screw-threaded hook 27 which extends through an 100 opening in a projection 28 formed on the trunnion 8. The tension of the spring 25 may be quickly and easily varied by means of a nut 29 disposed upon the screw-threaded portion of the hook 27 on the side 105 of the projection 28 opposite to the spring. As shown in Fig. 2, the force of the spring is exerted along a line that passes the motor pivot 7 on the side opposite to the motor, and, therefore, the effect of the spring is to 110

assist the rotation of the fan motor 10 in a counter clockwise direction, as indicated in Fig. 2. This rotation is transmitted to the fan motor 9 by means of the rod 20 which, as stated above, causes the fan motors to pivotally move in unison. Instead of the spring 25, helical springs may be placed around the bearing members 5 and 6, one end of each spring being in engagement with the adjacent trunnion support and thus assisting the action of centrifugal force. In this arrangement, each spring may be provided with means for adjusting the torsion of its coils and thereby varying the pressure which it exerts upon the fan trunnion.

The fan motors 10 and 11 may be supplied with electric energy in any convenient manner (not shown) which may be controlled by means of a switch button 30.

When the motors are horizontal, the supporting structure is at rest and the device is adjusted to revolve at relatively high speeds; the fan motors will, as stated above, assume positions in which their rear brackets approach the adjacent bracket arms. In this position, the axes of rotation of the two sets of fan blades, that is to say, the axes of the armature shafts of the motors, lie on opposite sides of the axis of revolution of the bracket 2. In this position, the spring 25 is under its greatest tension. When the fan blades are caused to rotate, the backward reaction or thrust of the fan motors, exercised in the direction of their axes of rotation, will exert a relatively large turning moment on the bracket 1, and the bracket will therefore be caused to rotate in a counter clockwise direction, indicated by the arrow *a* in Fig. 2. This rotation of the bracket sets up centrifugal forces which operate to turn the fan motors outward around their respective inclined pivots in opposition to the force of gravity. In thus turning the fan motor, centrifugal force is assisted by the tension of the spring 25, and the outward pivotal movement of each fan motor is continuous until the centrifugal force, together with the tension of the spring, are exactly balanced by the component of the thrust of the fan blades that tends to rotate the fan motor in a clockwise direction around its pivot, plus the weight of the motor multiplied by the sine of the angle to which its pivot is inclined. The proportions of the parts and the tension of the spring are so adjusted that, when the axes of the fan motors are horizontal, these opposing forces balance each other when the motors are in approximately the position shown in Fig. 2. The moment arm through which the motor thrust acts in driving the bracket around the axis of the hanger 2 is determined by the sum of the perpendicular distances from this axis to the projected axes of rotation of the fan motors. This com-

bined distance is designated D in Fig. 2 and varies with the retarding force and downward tilt of the fans. The speed of rotation of the bracket may be varied by manipulating the nut 29 to change the tension of the spring 25. For example, if the tension of the spring is increased, less centrifugal force will be necessary to bring the motors to a position of stable equilibrium with reference to their inclined pivots, and this position of equilibrium will therefore be reached while the bracket is rotating at relatively low speed. The speed of rotation of the bracket may likewise be increased within wide limits by lessening the tension of the spring 25. In practice, I have found that the speed of rotation of the bracket may readily be varied between 5 and 20 revolutions per minute.

The forces discussed above are complicated when the fan motors are tilted about their horizontal pivots in the trunnions 8 and 9. When the fan motors are so tilted, the horizontal component of the reactive thrust of each fan motor that tends to impart turning movement to the motor and to the bracket is diminished by the cosine of the angle through which the axis of the fan motor is tilted. At the same time, the horizontal component of the torque that drives the blades is added to or subtracted from the turning moment exerted upon the bracket, and is proportional to the sine of the angle of tilt. The direction in which the motor torque affects the turning moment exerted upon the bracket depends upon the direction in which the fan blades revolve. I prefer that the torque of the motors shall assist the rotation of the supporting bracket, though the device may be adjusted to operate with the torque opposing the rotation of the bracket. Under these operating conditions, rotating force acting to move each fan motor outwardly around its inclined pivot is made up of the centrifugal force impressed upon the motor, plus the tension of the spring, and plus (or minus) the torque of the motor multiplied by the sine of the angle through which the fan is tilted. When this compound force is balanced by the motor-turning component of the fan thrust, plus the weight moment of the motor multiplied by the sine of the angle of inclination of the pivot, the fan motor will be in stable equilibrium with reference to its pivot.

The downward tilting of the fan motors also causes variations in the relative positions of the parts of the device during its operation. If the motors are tilted through an angle of about 30° , and the fan blades rotate in such a direction that the torque of the motors assists in rotating the bracket, the torque effect of the motors is just sufficient to rotate the bracket with the fan motors in their position of stable equilibrium, and

the axes of the fan motors will then pass through the axis of rotation of the bracket, the distance D, Fig. 2, being reduced to zero. When the fan motors are tilted still further, the torque effect is greater than the retarding moment required to be overcome in rotating the bracket, and this excess torque causes the fan motors to rotate farther outward until the backward thrust effect balances the excess torque effect. The axes of the motors are then on opposite sides of the axis of rotation of the bracket from their positions shown in Fig. 2.

It will be evident that revolving fans constructed in accordance with the principles discussed above are adapted to revolve at a variety of speeds, which may be readily selected and varied by simple manipulation of the nut 29 which controls the tension of the spring 25, since this tension is the only variable factor of the forces which cause the structure to revolve when the fan motors are disposed at a given inclination. It will also be evident that the fan motors are caused to move in unison by means of the rod 20, which maintains the fan motors in equal angular relations to the bracket, and that the driving forces impressed upon the structure are always regulated in accordance with the resistance to turning offered by the structure.

Numerous structural modifications may be effected in my device without departing from the principles of my invention, and it is therefore to be understood that my invention comprehends all such changes and modifications as fall within the scope of the appended claims.

I claim as my invention:

1. The combination with a rotatable supporting member provided with an inclined pivot member, of a rotatable fan pivotally mounted upon the said pivot member, whereby the said fan tends to rotate under the influence of gravity around the said pivot.

2. The combination with a rotatable supporting member provided with an inclined pivot for supporting a rotatable fan, of means for opposing the tendency of the said fan to rotate under the influence of gravity around the said pivot.

3. The combination with a rotatable supporting member provided with an inclined pivot for supporting a rotatable fan, of a spring adapted to oppose the tendency of the said fan to rotate under the influence of gravity around the said pivot.

4. The combination with a rotatable supporting member provided with an inclined pivot member, of a rotatable fan pivotally supported by the said pivot member and adapted to be pivotally moved thereon by centrifugal force during the rotation of the said supporting member, and a stop associated with the said supporting member for

limiting the degree of such pivotal movement of the said fan.

5. The combination with a rotatable supporting member provided with an inclined pivot member, of a rotatable fan pivotally mounted upon the said pivot member and adapted to be pivotally moved in one direction under the influence of gravity and also adapted to be pivotally moved in the opposite direction by centrifugal force during the rotation of the said supporting member.

6. The combination with a rotatable supporting member provided with an inclined pivot member, of a rotatable fan pivotally mounted upon the said pivot member and adapted to be pivotally moved in one direction under the influence of gravity and also adapted to be pivotally moved in the opposite direction by centrifugal force during the rotation of the said supporting member, and means for assisting the action of centrifugal force in pivotally moving the said fan.

7. The combination with a rotatable supporting member provided with an inclined pivot member, of a rotatable fan pivotally mounted upon the said pivot member and adapted to be pivotally moved in one direction under the influence of gravity and also adapted to be pivotally moved in the opposite direction by centrifugal force during the rotation of the said supporting member, and a spring for assisting the action of centrifugal force in pivotally moving the said fan.

8. The combination with a rotatable supporting member provided with an inclined pivot member, of a rotatable fan pivotally mounted upon the said pivot member and adapted to be pivotally moved in one direction under the influence of gravity and also adapted to be pivotally moved in the opposite direction by centrifugal force during the rotation of the said supporting member, a spring for assisting the action of centrifugal force in pivotally moving the said fan, and means for varying the effect of the said spring.

9. The combination with a rotatable supporting member provided with an inclined pivot member, of a rotatable fan pivotally mounted upon the said pivot member and adapted to be pivotally moved in one direction under the influence of gravity and also adapted to be pivotally moved in the opposite direction by centrifugal force during the rotation of the said supporting member, and a tension spring secured at one end to the said supporting member and at the other end to the said fan, the said fan and the line along which the tension of the said spring is exerted being disposed on opposite sides of the said pivot member.

10. The combination with a rotatable supporting member provided with an inclined pivot member, of a rotatable fan pivotally

mounted upon the said pivot member and adapted to be pivotally moved in one direction under the influence of gravity and also adapted to be pivotally moved in the opposite direction by centrifugal force during the rotation of the said supporting member, a spring secured at one end to the said supporting member and at the other end to the said fan, and means for manually varying 10 the tension of the said spring.

11. The combination with a rotatable supporting member, of two fans pivotally supported on the said member, and a rod pivoted at its ends to the said fans.

12. The combination with a rotatable supporting member, of two fans pivotally supported on the said member, and a rod pivotally secured, at its ends, to the said fans, the points of attachment of the ends of the 20 said rod to the said fans being substantially equidistant from the respective pivotal axes of the said fans.

13. The combination with a rotatable supporting member, of two fans pivotally supported on the said member, and a rod pivotally secured, at its ends, to the said fans, 25

the points of attachment of the ends of the said rod to the said fans being substantially equidistant from the respective pivotal axes of the said fans and being so disposed with 30 relation to the said pivotal axes that the said fans are permitted to move pivotally in the same direction.

14. The combination with a rotatable supporting member provided with an inclined 35 pivot member, of a rotatable fan pivotally supported by the said pivot member and adapted to be pivotally moved thereon by the reaction of the said fan and by centrifugal force during the rotation of the said 40 supporting member, and a stop associated with the said supporting member for limiting the degree of such pivotal movement of the said fan.

In testimony whereof, I have hereunto 45 subscribed my name this 30th day of Dec. 1914.

OLIVER S. JENNINGS.
